[57] **CLAIM**

The ornamental design for an articulator for artificial dentures, as shown and described.

DESCRIPTION

FIG. 1 is a top and front perspective view of an articulator for artificial dentures, showing my new design;

FIG. 2 is a front view thereof;

FIG. 3 is a rear view thereof;

FIG. 4 is a bottom plan view thereof;

FIG. 5 is a top plan view thereof;

FIG. 6 is a side elevational view thereof from one side;

FIG. 7 is a side elevational view from the side opposite that shown in FIG. 6; and

FIG. 8 is a top perspective view thereof, taken from the side opposite that shown in FIG. 1, and showing the articulator in its fully open position.

FIG. 1

FIG. 2

FIG. 3

FIG. 4

FIG. 7

FIG. 8
